VIDEOTELEPHONE TRANSCEIVER

Donald Michael Genaro, Haworth, and Thomas Joseph Kelly, Middletown, N.J., John Niel McGarvey, Drexel Hill, Pa., and Daniel Wescoat Tyler, Middletown, N.J., assignors to Bell Telephone Laboratories, Incorporated, Murray Hill, N.J.

Filed Oct. 15, 1974, Ser. No. 514,401

Term of patent 14 years

Int. Cl. D14—03

U.S. Cl. D26—14 A

FIG. 1

FIG. 2

FIG. 3

FIG. 1 is a right front perspective view of a video-telephone transceiver showing our new design;

FIG. 2 is a front view of the videophone transceiver shown in FIG. 1;

FIG. 3 is a right side view of the videophone transceiver shown in FIG. 1;

FIG. 4 is a rear view of the videophone transceiver shown in FIG. 1; and

FIG. 5 is a top plan view of the videophone transceiver shown in FIG. 1.

We claim:

The ornamental design for a videophone transceiver, substantially as shown and described.
